UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,308,749.

Specification of Letters Patent.

Patented July 1, 1919.

Application filed May 10, 1916. Serial No. 96,493.

To all whom it may concern:

Be it known that I, ARTHUR BESSEY SMITH, a citizen of the United States of America, and a resident of Evanston, county 5 of Cook, and State of Illinois, have invented certain new and useful Improvements in Automatic Telephone Systems, of which the following is a specification.

While my invention relates in general to 10 automatic telephone systems, it is concerned more particularly with methods of automatic calling between widely separated automatic exchanges connected by toll or long distance lines.

15 It has long been the common practice, in systems of the above general character, to utilize the long distance lines for telegraphic purposes simultaneously with their use telephonically, the telephone connections 20 being established manually in the old and well known manner. Recently it has in some instances been considered advisable to provide means whereby the long distance connections could be established automatically 25 between the various exchanges, thereby considerably expediting the service. Such operation, however, to the best of my present knowledge, has heretofore made it necessary to dispense with the telegraph circuits. 30

It is the object of the present invention to provide circuit arrangements and devices whereby long distance lines arranged with superimposed telegraph circuits are adapted 35 for automatic operation without necessitating the elimination of such telegraph circuits. I employ the usual simplex circuit superimposed either on a single line or on a phantom line, which simplex circuit may 40 be used for operating telegraph instruments or any other devices capable of being operated by direct current. To operate the 45 automatic switches, I provide at each end of the above mentioned simplex circuit a branch circuit, the branch at one end containing a relay and the branch at the other end containing a source of alternating current. I provide, furthermore, means whereby the direct and alternating currents are 50 confined to their respective circuits at each end, thereby making it possible to telegraph and set up an automatic connection simultaneously over the same line.

The particular means employed in attaining the foregoing objects will be set forth and described in detail hereinafter; reference being had to the accompanying drawings, in which Figures 1, 2, and 3, when taken in order with the lines at the ends thereof in alinement, represent diagrammatically a complete circuit connection between a calling substation A and a called substation A' in a system embodying the principles of my invention. The said connection has been established through the 60 medium of the cord circuit P, toll line 51-52, repeater E, and connector F.

Referring now to Fig. 1, the substation A may be of any suitable or approved type, and as shown herein consists of the usual 70 common battery arrangement in which the transmitter and receiver are connected in series. The line conductors 12 and 13 have allotted to them at the exchange the usual line and cut-off relays 14 and 15, the answering jack J, and the lamp signal L.

The cord circuit P likewise may be of any suitable type. As shown herein it comprises essentially a bridged relay 21 which, in conjunction with sleeve relay 20, controls the supervisory lamp L'; and the ringing up locking relay 22 which, in conjunction with sleeve relay 23, controls the supervisory lamp L². Keys K' and K³ are ringing keys, while key K² is a listening key 85 adapted, when operated, to bridge the operator's head set across the two strands of the cord circuit.

The toll line 51-52 may be provided at the exchange in which the line of substation A terminates with the regular multiple jacks, one of which is shown at J'. Associated with the jack J' in the usual manner is shown a drop 30 and a cut-off relay 31. The remaining equipment directly associated with jack J' has been indicated collectively by the reference character M and comprises a calling device S, a calling device key K⁴, a switching relay 32, an alternating current generator 48, and what I term a barrier, consisting of the condenser 34 and the reactance coil 33. The operation and functions of this apparatus can best be described later in connection with the detailed description of the operation. 100 It may be mentioned at this time, however,

that the generator 48 delivers current of a frequency somewhat higher than the usual commercial power frequencies. I have found that a frequency of 200 cycles per second gives good results in practice although I do not limit myself to any particular frequency. It may be mentioned, furthermore, that to enable it to operate with the circuits shown, the calling device 10 S should be of the two-wire type, such, for example, as is shown in British patent to S. G. S. Dicker, No. 29,654 of 1910.

At the distant exchange the toll line 51-52 is provided with a multiple jack J² 15 and the associated drop 165 and cut-off relay 166. Relay 160 is an alternating current relay so designed and constructed that it will maintain its armature continuously attracted when its windings are traversed 20 by alternating current. The condenser 164 and reactance coil 163 constitute a barrier similar to the one at the other end of the line which has been previously mentioned.

The toll line 51-52 is also provided at 25 the distant exchange with a repeater E to which it is connected through contact springs of the cut-off relay 166. The repeater E may be of the general type of repeater disclosed in U. S. Letters Patent No. 30 1,136,912, granted April 20, 1915, to Talbot G. Martin, although the circuits are somewhat modified to enable it to operate in conjunction with the rest of the equipment. The operation and functions of the various 35 relays of the repeater will be described fully hereinafter.

Directly connected with the repeater E is shown a connector switch F (Fig. 3) which may be of the general type of connector 40 switch disclosed in U. S. Letters Patent No. 815,176, granted March 13, 1906, to Keith, Erickson, and Erickson; being, however, more nearly of the particular type disclosed in British patent to the Automatic Telephone Mfg. Co., No. 2270 of 1914. A connector switch of the foregoing general description may be given access to a plurality of subscribers' lines and is operable in response to digits of a called number to establish connection with any one of the lines 45 to which it has access. It will be understood, of course, that selector switches may be inserted between the repeater E and the connector F in order to increase the capacity of the system. Selectors suitable for 50 this purpose are shown in the British patent to the Automatic Telephone Mfg. Co., No. 2543 of 1914.

One of the lines accessible to connector F 55 is shown in Fig. 3 as extending to the substation A', which, as illustrated, is an automatic substation of well known type. A similar substation is shown and described in British patent to Martin, No. 1419 of 1910.

The line of substation A' may be provided 65 at the exchange with an individual line switch C which as shown in Fig. 3 is similar to the line switch shown and described in U. S. Letters Patent No. 1,078,690, granted Jan. 17, 1912, to Frank Newforth. Since 70 line switches of the above type are well known an extended description will not be given. It will be sufficient to say that through the medium of line switch C the line of substation A', when calling, is given 75 access to a plurality of selector switches, or connector switches as the case may be, whereby connections may be established with other local lines in well known manner. 80

Referring now to Figs. 1 and 2, it will be seen that the toll line 51-52 is provided at each end with a repeating coil through the medium of which it is connected inductively with the line equipments. The provision of the repeating coils renders possible the formation of a simplex circuit including the two sides of toll line 51-52 in parallel. In connection with this simplex circuit I have shown diagrammatically a 90 simple Morse telegraph circuit including the battery B', key K', and relay coil 80 in Fig. 1, and the relay coil 81, and key K^o in Fig. 2. The two branch circuits which have been previously mentioned as being essential to 95 my invention may be clearly seen, one at each end, extending from the junction of the line winding of the repeating coil to the inductance of the barrier.

For supplying direct current for operating and talking purposes I have shown in each exchange a battery having its positive pole grounded, and in connection with the telegraph circuit I have shown an additional battery having its negative pole grounded. 105 Associated with the connector F I have shown a generator Gen for supplying ringing current, an interrupter I for supplying intermittent ringing impulses, and a busy signaling machine Q. 110

Having given a general description of the apparatus, I will now proceed to a more detailed explanation of the operation of the same. For the purposes of this explanation it will be assumed that the subscriber at substation A wishes to obtain connection with the subscriber at substation A', this being the completed circuit connection shown in the drawings and previously referred to. Inasmuch as a great deal of the 120 equipment shown is well known and has been described fully in the publications referred to, the operation of such apparatus will be described in a more or less general manner.

Upon the removal of the receiver at substation A to initiate the call a circuit is completed for the line relay 14, thereby light- 125

- ing the line lamp L. In this manner the attention of the operator is attracted and she will respond by inserting the answering plug of cord circuit P in the jack J. A circuit is thereupon completed including the sleeve relay 20 and the cut-off relay 15, whereby the line relay 14 is disconnected and the lamp L is extinguished. The operator may now throw her listening key K² and 5 converse with the calling subscriber, obtaining the usual information regarding the name and number of the party wanted, etc.
- In the present case, since the wanted subscriber is located in a distant exchange to 10 which the toll operator has access over the toll line 51—52, the operator will insert the calling plug of cord circuit P in the jack J', the idle or busy condition of the toll line being first determined by testing with the tip of the plug in the regular manner. Upon 15 the insertion of the plug, a circuit is completed over the sleeve of the jack as follows: ground at G², winding of cut-off relay 31, sleeve of jack J', sleeve of plug, and winding of relay 23 to battery B. The sleeve relay 23, upon energizing, disconnects the test wire from the upper strand of the cord and connects ground to the armature of supervisory relay 22 (of no consequence at this 20 time, however). The cut-off relay 31, upon energizing, disconnects the drop 30 and prepares a locking circuit for relay 32.
- Since the connection is to be established automatically, the operator will now throw 25 the calling device key K⁴, thereby inserting the calling device S in a circuit to be presently described and also closing a circuit for relay 32 as follows: ground at G³, contact springs 36 and 35, and winding of relay 32 to battery B. Upon attracting its armature, 30 relay 32 inserts its winding in the following locking circuit: ground at G⁵, contact springs 42 and 41, contact springs 46 and 45 and winding of relay 32 to battery B.
- As a further result of the energization of 35 relay 32, the following circuit is completed to the distant exchange: ground at G⁴, A. C. generator 48, contact springs 44 and 43, calling device S, contact springs 38 and 37, condenser 34, reactance coil 33, windings 75 and 40 76 of repeating coil R' in parallel, line conductors 51 and 52 in parallel, windings 177 and 178 of repeating coil R² in parallel, reactance coil 163, condenser 164, and windings of alternating current relay 160 to 45 ground at G¹⁰. The reactance coils 33 and 163 and the condensers 34 and 164 are of such inductance and capacity, respectively, that the above circuit is resonant to the frequency of generator 48, whereby sufficient current is permitted to flow to operate the alternating current relay 160. It will be observed that in addition to the path to ground 50 by way of alternating current relay 160,

there are two other possible paths by way of which current from generator 48 might find its way back to ground at G⁵. These alternative or shunt paths, however, each include one or more telegraph relays which are of such high impedance as to permit very little of the high frequency alternating current to pass. The telegraph relays are not affected by what current does leak through them by reason of their comparatively heavy armatures and the adjustment of their retractile springs. I have found it desirable, in order to increase the impedance of the telegraph branches at each end, to insert impedance coils in series therewith. These coils may be connected as shown in the drawings. 55

To proceed with the operation, the A. C. relay 160, upon attracting its armature, completes a circuit including the line relays of repeater E over the following path: ground at G¹¹, winding of relay 211, contact springs 168 and 169, winding 191 of repeating coil R², armature and contact of A. C. relay 160, winding 190 of repeating coil R², contact springs 171 and 170, and winding of relay 210 to battery B². Upon energizing, relay 210 closes a circuit for the slow-acting relay 213 as follows: ground at G¹², contact springs 217 and 218, and winding of relay 213 to battery B². Relay 213 attracts its armature, and by means of contact springs 232, 233, and 234 shifts the sleeve of jack J² from its normal connection by way of conductors 170^a and 171^a to relay 166, to battery B² by way of conductor 170^a and resistance 239. In this manner a guarding potential is placed on the sleeve of jack J²; and, furthermore, should an operator disregard her busy test or plug into jack J² accidentally she will not release a connection already established automatically for the 105 cut-off relay 166 has had its circuit opened as explained. Relay 213 also prepares, by means of contact springs 237 and 238, an energizing circuit for relay 214; and, by means of contact springs 235 and 236, a 110 locking circuit for relay 212.

Relay 211, upon energizing, closes a circuit for the line relay 250 of the connector F over the following path: ground at G¹⁵, lower winding of line relay 250, normally 115 closed contacts of relay 253, conductor 243, contact springs 220 and 219, contact springs 230 and 231, winding of reactance coil 215, conductor 240, contact springs 226 and 225, conductor 242, normally closed contacts of 120 relay 253, and upper winding of line relay 250 to battery B². The line relay 250 energizes over the foregoing circuit and thereby closes an energizing circuit from ground at G¹⁶ for the slow acting relay 251 which relay, upon energizing in turn, prepares a circuit in the well known manner for the vertical and rotary magnets 255 and 256. 125

The operator at the originating exchange 4 may now proceed to dial the wanted number. Upon the operation of the calling device S in accordance with the first digit, the 5 impulse springs of the calling device are separated momentarily a number of times, interrupting each time the previously described circuit including the generator 48 and the A. C. relay 160. As a result of these 10 interruptions of its circuit, relay 160 deenergizes a corresponding number of times and at each deenergization breaks the circuit of relays 210 and 211 of the repeater E. Whence it will be seen that relays 210 and 15 211 will be deenergized a number of times corresponding to the first digit of the called number.

At the first deenergization of relay 210, a circuit is completed for the slow acting relay 214 as follows: ground at G¹², contact springs 217 and 216, contact springs 238 and 237, and winding of relay 214 to battery B². Relays 213 and 214, being slow acting, retain their armatures in operated position during impulses, after which relay 214 retracts its armature. In its energized condition, relay 214 disconnects the conductors 242 and 243 from the conductors 240 and 241, respectively, and from the normally bridged coil 25 215; substitutes for the latter a direct path by way of contact springs 220 and 219 and contact springs 230 and 229; and completes an initial energizing circuit for relay 212 as follows: ground at G¹⁴, winding of relay 212, 30 and contact springs 227 and 228 to battery B². Relay 212 locks itself in an obvious manner by closing contact springs 221 and 222; and also, by separating contact springs 223 and 224, opens the circuit of the line 35 drop 165.

Relay 211, at each deenergization, breaks the circuit of the line relay 250 of the connector F. In response to these interruptions of its circuit, the line relay 250 deenergizes a 45 corresponding number of times, sending at each deenergization an impulse to the slow acting relay 252 and the vertical magnet 255 in series, side switch wiper 264 being in its first position. In response to these impulses 50 the vertical magnet operates to raise the switch shaft until the wipers 270, 271, and 272 stand opposite the horizontal level containing the line contacts of substation A'. The relay 252, being slow acting, retains its 55 armature attracted during the series of impulses and thereby maintains an energizing circuit for the private magnet 259. At the end of the series of impulses the relay 252 and the private magnet deenergize, the latter controlling the side switch wipers in the 60 usual manner to advance them to their second position.

The operator may now manipulate the calling device S in accordance with the final

digit of the desired number, resulting as before in deenergizations of the A. C. relay 160. The consequent interruptions are repeated as before described until they affect the line relay 250 of the connector F, which now, side switch wiper 264 being in its second position, sends impulses to the relay 252 in series with the rotary magnet 256. In response to these impulses the rotary magnet operates to rotate the switch shaft until the wipers 270, 271, and 272 are brought to rest 70 upon bank contacts 273, 274, and 275, which are the contacts associated with the line of substation A'. The private magnet is again controlled by the relay 252 responsive to the final series of impulses to advance the side 75 switch wipers to their third position.

As side switch wiper 263 comes into its third position, a circuit is completed from ground at G¹⁷ by way of wiper 271 and bank contact 274 to the holding winding 330 of 80 line switch C. Upon energizing, the holding winding operates the cut-off armature 331, whereby the line conductors of substation A' are disconnected from their connections in line switch C. Ground from G¹⁷ also extends to multiple contacts similar to contact 85 274 in the banks of other connectors of the group, thereby making the line busy to other calls. By the advance of side switch wipers 261 and 262 to their third positions the connection is completed to the called line. By the advance of side switch wiper 264 to its third position a circuit is completed for the ringing relay 260, which is operated intermittently thereafter by the interrupter I 90 to signal the subscriber at substation A'. When the called subscriber removes his receiver in response to the ringing of his bell a circuit is completed in the well known 95 manner for the double wound back bridge 100 relay 253 (ringing relay 260 being temporarily deenergized) which relay, upon energizing, reverses the incoming line conductors (of no particular consequence) and also completes a circuit for the ring cut-off relay 105 258. The ring cut-off relay, upon attracting its armature, locks itself to ground at G¹⁷ and at the same time opens the circuit of the ringing relay 260.

At the originating exchange, when the operator has completed the dialing of the required number she may now restore the calling device key K⁴, thereby making the calling device S available for use in other connections. Assuming that the subscriber at 115 substation A has replaced his receiver after placing his call, the operator will now operate the ringing key K' to again call him to the telephone. In response to the ringing of his bell the calling subscriber at substation A may now remove his receiver from the hook, when the required connection will have been completed. Current for the trans- 120 125

mitter at the calling substation is supplied through the windings of the supervisory relay 21 of the cord circuit P, while current for the transmitter of the called substation 5 is supplied through the windings of the double wound back bridge relay 253 of the connector F. The complete path for voice currents has been drawn in heavy lines and should be apparent without further explanation.

When the conversation is finished both subscribers will replace their receivers. Upon replacing the receiver at substation A the relay 21 is deenergized, thereby lighting the supervisory lamp L'. By this means the operator is informed that the conversation is at an end, whereupon she may remove both plugs of cord circuit P from the jacks. The removal of the plug from jack 15 J removes ground from cut-off relay 15, whereby the individual apparatus associated with substation A is restored to normal condition. The removal of the plug from jack J' breaks the circuit of relay 31. Relay 20 31, upon deenergizing, breaks the locking circuit of relay 32, which relay, upon deenergizing in turn, disconnects the generator 48 from the circuit of the A. C. relay 160 (Fig. 2). The relay 160 thereupon retracts 25 its armature and breaks the circuit of relays 210 and 211 of repeater E. By the deenergization of relay 211 the circuit of the line relay 250 of the connector F is broken, whereupon all the automatic switches are 30 restored to normal position in the well known manner.

If the line of substation A' had been busy when called, the connector H would have operated after the final series of impulses 40 to connect a lead from the busy signaling machine Q with one side of the calling line, the side switch wipers being held in the second position for this purpose and to prevent connection with the called line. Upon 45 receiving the busy signal, the operator at the distant exchange removes the plug from jack J' whereupon the apparatus is restored to normal as hereinbefore described.

The toll line 51-52 is adapted for regular manual operation as well as for automatic operation and I will now describe in a cursory manner how this is accomplished. Assuming that the operator at the originating exchange desires to establish a connection manually with the aid of the operator 55 at the distant exchange, she will use the same cord circuit as before, but instead of throwing the calling device key K⁴ she will operate the ringing key K³ in her cord circuit. 60 As a result, the drop 165 at the distant exchange is actuated, thereby signaling the operator there stationed, who will respond by inserting the plug of a cord circuit similar to cord circuit P in jack J². The oper-

ators at the two exchanges may now converse 65 or establish a connection between local subscribers in their respective exchanges as desired. Interference between manual and automatic connections is absolutely prevented. Whenever a plug is inserted in the 70 jack J² of toll line 51-52, the drop and the automatic repeater associated therewith are disconnected. Conversely, whenever the repeater is operated from the distant end, a busy potential is placed on the sleeve of the 75 jack and the cut-off relay is disabled, all as has been described. It is important to note in this connection that while the operator at the No. 2 exchange cannot interfere with automatic connections established by operators in the No. 1 exchange to the extent of disconnecting such connections, she is enabled, nevertheless, to supervise such a connection by simply disregarding the busy 80 test and plugging into the jack. This feature is often a valuable one.

Referring now to the telegraph equipment, the signaling impulses transmitted over the simplex circuit are of comparatively low frequency, if such term may be 90 used with reference to interruptions of direct current, and the barriers located in the branches at each end effectually prevent the shunting of such impulses from their proper path. It will be seen, therefore, that telegraphic signaling and the operation of automatic switches may occur simultaneously.

While I have shown and described in the foregoing a certain specific embodiment of my invention it will be evident to persons skilled in the art that many modifications may be made without further invention. For example, the exchange to which substation A is connected might be an automatic exchange, whence it would naturally follow 105 that the toll line 51-52 should be adapted for automatic operation in both directions. Such adaptation may be made by simply duplicating the equipment at each end at the other end. Also, instead of the simple 110 Morse telegraph circuit shown, more modern and efficient systems may be used, such as well known duplex or quadruplex systems. Or, if desired, apparatus other than telegraph equipment may be operated, care being taken to include sufficient impedance at 115 each end of the circuit to prevent shunting of the alternating current from the automatic switch operating circuit.

In view of these considerations I do not 120 wish to limit my invention to the particular embodiment shown but desire rather to include and have protected by Letters Patent all forms and modifications thereof which may come within the scope of the appended 125 claims.

What I claim as my invention is:

1. In a telephone system, a line connecting

- two exchanges, means including said line and an automatic switch at one exchange for connecting subscribers' lines in the two exchanges, a telegraph circuit superimposed on said line, a branch of said circuit at one end containing a condenser and a controlling relay for said switch, and a branch of said circuit at the other end containing a condenser and a source of alternating current for operating said controlling relay.
2. In a telephone system, a line connecting two exchanges, means including said line and an automatic switch at one exchange for connecting subscribers' lines in the two exchanges, a telegraph circuit superimposed on said line, a controlling circuit for said switch including the superimposed portion of said telegraph circuit, a source of alternating current in said controlling circuit at one end, and a relay in said controlling circuit at the other end.
3. In a telephone system, a line connecting two exchanges, means including said line and an automatic switch at one exchange for connecting subscribers' lines in the two exchanges, a telegraph circuit superimposed on said line, a controlling circuit for said switch including the superimposed portion of said telegraph circuit, a source of alternating current in said controlling circuit at one end, a relay in said controlling circuit at the other end, and an electrical tuning device in said controlling circuit whereby the said controlling circuit is made resonant to the frequency of said alternating current source.
4. In a combined telephone and telegraph system, means including a toll line and an automatic switch for establishing telephone connections, a direct current telegraph circuit, a controlling circuit for said switch, said circuits having a common portion superimposed on said toll line, a source of alternating current in said controlling circuit at one end, and a controlling relay for said switch in said controlling circuit at the other end.
5. In a combined telephone and telegraph system, means including a toll line and an automatic switch for establishing telephone connections, a direct current telegraph circuit, a controlling circuit for said switch, said circuits having a common portion superimposed on said toll line, a source of alternating current in said controlling circuit at one end, a controlling relay for said switch in said controlling circuit at the other end, an electrically tuned barrier impervious to direct current in said controlling circuit at each end, and a device offering high impedance to alternating current in said telegraph circuit at each end.
6. In a telephone system, a line connecting two exchanges, means including said line and an automatic switch at one exchange for connecting subscribers' lines in the two exchanges, a telegraph circuit superimposed on said lines so as to include conductors in both sides of a section of the talking circuit in parallel, a branch of said circuit at one end containing a condenser and a controlling relay for said switch, and a branch of said circuit at the other end containing a condenser and a source of alternating current for operating said controlling relay.
7. In a telephone system, a line connecting two exchanges, means including said line and an automatic switch at one exchange for connecting subscribers' lines in the two exchanges, a telephone for each line, said switch also for establishing a talking circuit between telephones of the connected lines, a telegraph circuit superimposed on said lines so as to include conductors in both sides of a section of the talking circuit in parallel, a controlling circuit for said switch including the superimposed portion of said telegraph circuit, a source of alternating current in said controlling circuit at one end, and a relay in said controlling circuit at the other end.
8. In a telephone system, a line connecting two exchanges, means including said line and an automatic switch at one exchange for connecting subscribers' lines in the two exchanges, a telephone for each line, said switch also for establishing a talking circuit between telephones of the connected lines, a telegraph circuit superimposed on said lines so as to include conductors in both sides of a section of the talking circuit in parallel, a controlling circuit for said switch including the superimposed portion of said telegraph circuit, a source of alternating current in said controlling circuit at one end, and a relay in said controlling circuit at the other end.
9. In combination, a telephone circuit for talking between two telephones, a second circuit for telegraphing purposes, and a third circuit for controlling the continuity of said talking circuit, said second and third circuits superimposed on said talking circuit, means whereby current may flow over all of said circuits simultaneously.
10. In combination, a telephone circuit for talking between two telephones, a second circuit for telegraphing purposes, a third circuit for controlling the continuity of said talking circuit, said second and third circuits superimposed on said talking circuit, means whereby current may flow over all of

said circuits simultaneously, and means for preventing interference between said circuits.

11. In combination, a telephone circuit for talking between two telephones, a second circuit for telegraphing purposes, a third circuit for controlling the continuity of said talking circuit, said second and third circuits superimposed on said talking circuit so as

to include conductors in both sides of a section of the talking line in parallel, means whereby current may flow over all of said circuits simultaneously, and means for preventing interference between said circuits.

Signed by me at Chicago, Cook county, 15 State of Illinois, this 19th day of April, 1916.

ARTHUR BESSEY SMITH.
